Dennell, Curtis & Hough

UNITED STATES PATENT OFFICE.

JASON BEMIS, OF OWATONNA, MINNESOTA.

GRAIN-TALLY.

SPECIFICATION forming part of Letters Patent No. 396,063, dated January 15, 1889.

Application filed June 7, 1888. Serial No. 276,321. (No model.)

To all whom it may concern:

Be it known that I, JASON BEMIS, a citizen of the United States, residing at Owatonna, in the county of Steele and State of Minnesota, have invented certain new and useful Improvements in a Combined Grain Measure and Register; and I do hereby declare the following to be a full, clear, and exact description of the invention, such as will enable others skilled in the art to which it appertains to make and use the same.

This invention relates to certain new and useful improvements in grain registers or tallies, and has for its object to simplify and cheapen and to otherwise improve upon this class of devices as heretofore constructed. The novelty resides in the peculiar combinations and in the construction, arrangement, and adaptation of parts, all as more fully hereinafter described, shown in the accompanying drawings, and then specifically defined in the appended claims.

I provide a simple hand device for keeping account of the number of bushels measured or weighed—one that will not be liable to get out of order and that is composed of few parts.

The invention is clearly illustrated in the accompanying drawings, which, with the letters of reference marked thereon, form a part of this specification, and in which—

Figure 1 is a side view illustrating my improvement. Fig. 2 is a central vertical section of the same. Fig. 3 is a vertical section on the line $x x$ of Fig. 1.

Reference being had to the details of the drawings by letter, A designates an elevator of any suitable and well-known construction, and B is a measure constructed to contain any desired number of bushels of grain. This measure is pivoted on a shaft, a , suitably journaled in an extension, b , of the elevator-frame, and is provided with an opening, b' , for the grain to enter, and through which it is discharged when the measure is reversed. In one end or head of the measure I provide an opening near the opening b' and cover the same with glass, mica, or other transparent substance, and through this opening it may be seen when the measure is filled.

C designates a bag or other receptacle ar-

ranged beneath the measure and into which the grain is discharged therefrom.

D is a sleeve around the measure to keep the opening b' therein closed while the said measure is in motion and to conduct any scattering grain into the bag beneath the same.

Fast on the end of the shaft a is a crank-arm, c , to the outer end of which is connected one end of a pitman, E, which is guided by a keeper, d , on the extension b of the elevator-frame. Inclosed within a suitable case, F, on the elevator-frame is the registering mechanism, which is as follows:

G G^2 are indicator-wheels journaled upon a common pivot, g , upon the side of the elevator-case, the larger wheel, G, being placed adjacent to the case, as shown.

H H^2 are spring-actuated dogs which are pivoted upon a common pivot, h , at the outer end of the pitman E, the opposite end of each of these dogs being provided with a hook, h^2 , adapted to engage the notches upon the registering wheels G G^2 , respectively.

J is a guard-flange which is secured upon the outer face of the wheel G and surrounds the wheel G^2 . This flange J is broken away at one of its sides, as shown at j . The dog H^2 rests upon the outer face of the flange during the revolution of the wheel until it reaches the point j , when it engages one of the notches of the wheel.

The teeth of the indicator-wheels are provided with a series of numbers, as is common in indicating devices of this character.

The operation of the device will be readily understood. The measure having been filled, the same is given a one-half revolution by means of the handle upon its side, and, in revolving, the pitman E is drawn toward the measure, carrying with it the dogs H H^2 , the engagement of the dog H with the wheel G serving to move the wheel slightly. The measure being now reversed, the pitman E is thrown back and the dog H^2 engages the next succeeding tooth upon the wheel G , which in turn is moved forward. This operation continues with each filling and emptying of the measure, so that by observing at any time the number upon the tooth of the wheel last acted upon by the dog the number of times that

the measure has been emptied may be determined. The numbers from 1 to 10, or from 1 to 100, as the case may be, may be marked upon the teeth of the wheel G and the higher numbers upon the wheel G², and, as the flange or guard J serves to prevent the engagement of the dog H² with the teeth of this wheel excepting once during its revolution, it will be readily seen that the higher numbers will be automatically recorded.

While I have shown and described a measuring device in which but two registering wheels are employed, it will be readily seen that a greater number of wheels may be employed if for any reason it should be considered desirable, and I do not propose to limit myself in this application to any specified number.

Having thus described my invention, what I claim to be new, and desire to secure by Letters Patent, is—

1. The combination, with the revolving measure, the crank-arm on the shaft thereof, and the pitman connected at one end to said crank-arm and the other end free of the

wheels or shaft of the registering mechanism, of the notched wheel having an annular notched flange, the smaller notched wheel within said flange, and the spring-actuated dogs on the free end of said pitman, substantially as and for the purpose specified. 30

2. The combination of the revolving measure, its shaft, the crank-arm on said shaft, the notched wheel provided with a notched flange, the smaller notched wheel within said flange, the pitman connected at one end to said crank-arm, with its other end free of said wheels and their shaft, the dogs pivoted to the free end of the pitman on a common pivot and engaging said wheels, and the springs on a common pivot and bearing one on each of said dogs, substantially as described. 35 40

In testimony whereof I affix my signature in presence of two witnesses.

JASON BEMIS.
